H. R. ELLIS. INVENTOR.

BY

Geo. P. Kimmel.
ATTORNEY.

UNITED STATES PATENT OFFICE.

HORACE R. ELLIS, OF MEADVILLE, PENNSYLVANIA.

WINDOW SCREEN.

Application filed July 3, 1922. Serial No. 572,622.

To all whom it may concern:

Be it known that I, HORACE R. ELLIS, a citizen of the United States, residing at Meadville, in the county of Crawford and State of Pennsylvania, have invented certain new and useful Improvements in Window Screens, of which the following is a specification.

This invention relates to detachable window screens, and has for one of its objects to provide a device of this character, adapted to be arranged between the partly or fully opened sash and the stool or sill member of a window, and with fastening means to prevent the detachment of the screen from the outside.

Another object of the invention is to provide a device of this character, formed of coacting overlapping sections and with means for holding the sections in distended position and provided with means for preventing the release of the sections from the outside.

With these and other objects in view, the invention consists in certain novel features of construction as hereinafter shown and described, and then specifically pointed out in the claims, and in the drawings illustrative of the preferred embodiment of the invention:—

Figure 1 is an elevation from the inside of the room of a part of a window, with the improved screen in position therein,

Fig. 2 is a section on the line 2—2 of Fig. 1,

Fig. 3 is a plan view of the screen device, detached and enlarged,

Fig. 4 is a section of the screen device, enlarged, and in section on the line 4—4 of Fig. 1,

Fig. 5 is an enlarged perspective view of one corner of the improved device.

Fig. 6 is a detached perspective view of one of the guide rods illustrating a modification in the construction.

The improved device includes a screen frame in coacting sections, each including upper rail members 10, lower rail members 11, an outer stile member 12 and an inner stile member 13. The members 10, 11 and 12 are preferably of wood, while the member 13 is preferably in the form of a metal strip, as shown.

Portions of the rail members 10 and 11 overlap and are "halved" as shown, so that

the size of the overlapping portions is not increased.

Attached at one side face of the upper and lower rail members 10 and 11 of one of the sections is a guide bar 14, each bar slidably engaging a guide keeper 15 on the other section, and attached to the other side face of the members 10 and 11 is a like guide bar 16 slidably engaging guide keepers 17, on the other section, as shown in Figs. 3 and 4. 60

The free ends of the guide bars 14 and 16 are outturned as shown at 18 and 19. By this means, the frame sections will be held in coactive relation and may be adjusted toward and away from each other, but cannot 70 be separated by reason of the outturned portions 18 and 19 engaging against the keepers 15 and 17, as will be obvious.

The screen material is of the usual kind and represented conventionally at 20, and attached as by cleats 21 at three of its edges to the members 10, 11 and 12, and attached at its remaining edge to a strip 22, preferably of metal. The strip 22 is turned at right angles to the inner face of the connecting strip 13 and is connected thereto by bolts or the like, 23. By this means the screen material may be drawn tightly into position. 80

The screen sections are designed to rest by their lower rail members 11 upon the sill or stool 24, between the frame and the casing members 25 and beneath the lower rail 26 of the lower sash, as shown in Figs. 1 and 2.

Attached to the stile members 12 of each section is a socket device 27, and seated in each socket is a locking rod 28, the adjacent ends of the rods being spaced a short distance when the screen sections are disposed in position in the window, as shown in Fig. 1. 90

Slidable on the rods 28 is a relatively long sleeve 29, and formed through the sides of the sleeve are apertures 30, the apertures corresponding in width to the distance between the confronting ends of the rods 28, and adapted to receive a locking device, such for instance as the bolt 31 of a padlock 32. 100

By this arrangement, the screen sections after being disposed in position in the window, and the fastening devices 31 and 32 applied, are firmly locked in position so long as the fastening devices are in position, and as the latter are inside the window, the 110

screen cannot be released and removed from the outside.

Attached to the upper rail members 10 are stops 33 to engage beneath the lower rail 26 5 of the sash, to prevent the sash from being lowered, to permit a person to enter the room by lowering the sash.

A plurality of dowel pins 34 will also be applied to the stile member 12 to enter sockets 10 in the inside stops 25, as an additional securing means.

To remove the screen, it is only necessary to detach the lock device 31—32, move the sleeve 29 wholly upon one of the rods 28, 15 detach one or both of the rods from its socket 27 and slide the sections toward each other, or draw the free end of one of the rods outwardly until it will pass the other rod when the screen sections are moved toward each other.

By this simple means an effectual burglar and sneak thief proof screen device is provided, which may be inexpensively manufactured and applied without structural 25 change to windows of various sizes by simply cutting the rods 28 to correspond to the width of the window.

The preferred embodiment of the invention is disclosed in the drawings and set 30 forth in the specification, but it will be understood that modifications within the scope of the claimed invention may be made in the construction without departing from the principle of the invention or sacrificing any 35 of its advantages.

If preferred the guide members 14 may

be constructed of round rods 35 as shown in Fig. 6 with the ends 36 and 37 directed in opposite directions, the ends 36 corresponding to the stops 18 of the member 14, and 40 the reversely directed ends 37 adapted to enter sockets in the members 10 and 11, the rods being secured in any suitable manner to the members 10 and 11, for instance by staples 38.

Having thus described the invention, what is claimed as new, is:

1. A window screen in coacting overlapping sections, rods attached to the respective sections with their confronting ends in 50 spaced relation, a sleeve engaging the confronting ends of the rods and having transverse apertures corresponding in length to the space between the ends of the rods, and a locking element disposed through the slots 55 and engaged by the ends of the rods.

2. A window screen in coacting overlapping sections, rods attached to the sections with their confronting ends in spaced relation, a sleeve engaging the confronting ends 60 of the rods and having transverse apertures corresponding in length to the space between the ends of the rods, a locking element disposed through the slots and engaged by the ends of the rods, guide rods attached 65 to one of the said sections, and guide keepers attached to the other section and slidably engaged by said guide rods.

In testimony whereof, I affix my signature hereto.

HORACE R. ELLIS.
